UNITED STATES PATENT OFFICE.

JOHAN EMIL FAGERSTRÖM, OF HUSQVARNA, ANDERS EDVARD JOHANSSON, OF GIŠEBO, AND GOTTFRID STREIJFFERT, OF Malmö, SWEDEN, ASSIGNS TO AKTIEBOLAGET UNIVERSITÄTSLUTAREN, OF Malmö, SWEDEN.

CLOSING DEVICE FOR BOTTLES OR OTHER VESSELS.

No. 910,998.

Specification of Letters Patent.

Patented Jan. 26, 1909.

Application filed March 2, 1907. Serial No. 360,182.

To all whom it may concern:

Be it known that we, JOHAN EMIL FAGERSTRÖM, railway station-master, Husqvarna, Sweden, ANDERS EDVARD JOHANSSON, manufacturer, Gisebo, Sweden, and GOTTFRID STREIJFFERT, merchant, Malmö, Sweden, subjects of the King of Sweden, have invented certain new and useful Improvements in Closing Devices for Bottles or other Vessels, of which the following is a specification, reference being made to the accompanying drawing.

The present invention relates to such devices for the closing of bottles or other vessels in which the closing part, or stopper, is permanently attached to the neck of the vessel by means of a link device, and which stopper, by means of another device, is locked fast on its seat, which is arranged in the neck of the vessel.

The object of the invention is to obtain an elastic, and at the same time, a good and secure tightening between the stopper and its seat, by the employment of a stopper of glass or other suitable hard material, whereby the use of rubber rings or disks, which are objectionable in hygienic respects, is avoided. This object is attained, partly by making the locking device (or said device and the link device) elastic in the longitudinal direction of the neck of the vessel, so that the said device (or devices) will hold the stopper against its seat with an elastic pressure of sufficient force, and also partly by giving the stopper a spherical form, so that the same can, while bringing about a good and secure tightening, take up any position on its seat (within that space within which its movement is limited by the link).

On the accompanying drawing there are shown, as examples, two closing devices or stoppers constructed in accordance with this invention and attached to necks of bottles.

Figures 1 and 2 show the one device, seen from two directions which are at right angles to each other, while Figs. 3 and 4 show, in the same way, the second device and Fig. 5 is a rear elevation of the invention illustrating the employment of an elastic link for the stopper.

In the form of construction shown in Figs. 1 and 2 the stopper 1 is in the usual way permanently attached to the bottle neck or head 2 by means of a wire bow 3, a strip of sheet

iron or some other device. To the head of the bottle there is, as usual, pivotally attached a lever 4, with which, also as usual, there is pivotally attached a bow 5, a hook or some other device, which, when the bottle is closed, keeps a projection on the stopper 60 pressed down, thereby keeping the closing or tightening part of the stopper pressed against its seat. In the form of construction now in question the connection between the lever 4 and the bow 5 consists, according to this invention, of a spiral spring 6, which at its one end is pivotally attached to the lever and at the other end is integral with the bow.

As is shown, the closing or tightening part 7 of the stopper 1 is of a spherical form, 70 which circumstance, together with the elastic pressure brought about by the spiral spring 6, causes a good and secure tightening.

In Fig. 1 there is shown, by means of dotted 75 lines, the relative positions of the parts at one instant during the closing. When the lever 4 is swung, from the position thus shown, downwards and inwards towards the neck of the bottle, the spiral spring 6 is 80 stretched, in consequence whereof the spherical part 7 of the stopper is made to lie against its seat with a powerful elastic pressure, when the device is completely closed, which is shown by full lines in Fig. 1. 85

In the closing device shown in Figs. 3 and 4 the bow 5 and the spiral spring 6 are replaced by a bow 6^a, which is shaped somewhat like an 8. In consequence of the shape mentioned this locking part is, as the spiral spring 6, elastic in the longitudinal direction of the neck of the vessel. 90

It is clear that the locking device and the link device can simultaneously be elastic in the longitudinal direction of the neck of the vessel. An elastic construction of the link is illustrated in Fig. 5, the link 3 being shown as somewhat 8-shaped.

The elasticity of the locking device or the link device can evidently be gained by the 100 help of other arrangements than those shown.

Having now described our invention, what we claim as new and desire to secure by Letters Patent is—

1. In a device of the character described, 105 the combination with the neck of a bottle, of a stopper having a spherical bearing surface adapted to seat in the bottle mouth, a bow

elastically yieldable longitudinally of the bottle for pivotally securing the stopper to the bottle, and elastically yielding locking means for locking the stopper on its seat.

- 5 2. In a device of the character described, the combination with the neck of a bottle, of a stopper having a spherical bearing surface adapted to seat in the bottle mouth, means elastically yieldable longitudinally of the bottle for pivotally securing the stopper to the bottle, and means elastically yieldable longitudinally of the bottle for locking the stopper to its seat.

In witness whereof we have hereunto set our hands in presence of two witnesses.
